Attorney.

UNITED STATES PATENT OFFICE.

HARRY ALPHONSE WIDMER, OF LONDON, ENGLAND, ASSIGNOR OF ONE-HALF TO
A. LEWIS (FINSBURY) LIMITED, OF LONDON, ENGLAND, A COMPANY OF GREAT
BRITAIN.

FASTENER.

Application filed October 9, 1926, Serial No. 140,660, and in Great Britain September 24, 1926.

This invention relates to a fastening device which may be used with containers fitted with flaps such as pouches, and purses, on trunks and bags, on straps or strap fittings such as shoe-fasteners and wrist watches, and in other cases where an easily operated reliable fastening which can be locked when required, is desired.

An embodiment of the invention is shown by way of example in the accompanying drawings, in which—

Figure 1 is a longitudinal sectional view, and

Figure 2 is a plan view partly in section.

The tab 1 is provided with a recess 2 in which is hinged the shoulder 3 provided with a spring 4 normally urging it upward into the position shown in Figure 2, the upward movement being limited by a projecting edge 5. In use the tab is pushed through the bridge 6 and held by the shoulder 3.

Within the body of the tab 1 is provided a lock 7 having a bolt 8. The lock mechanism may be of any desired kind and the form illustrated is only shown as an example. The bolt 8 has a rearward extension 9 guided by a slot 10 on a rivet 11. The key turns on a pin 12, its operating blade engaging in a notch 13 in the extension 9. The spring 14 has a projection which enters in a notch 15 when the bolt is retracted and behind the

extension at 16 when the bolt is shot. The key in turning first raises the spring by pressing at 17 thus disengaging the projection and then shooting or retracting the bolt. 35

What I claim is:—

1. A fastening device comprising a bridge member, a tab adapted to pass through said bridge member, a resiliently mounted shoulder on said tab adapted to be depressed when passing under said bridge, and a lock mounted on the said tab independently of said shoulder having a bolt which when shot projects beneath said shoulder and retains it in its uppermost position. 40

2. A fastening device comprising a bridge member, a metal tab with a recess in its upper face, a spring set in said recess, a bent plate forming a shoulder pivotally mounted in said recess above said spring and adapted to be depressed against the influence of said spring when passing under said bridge, a stop on said shoulder plate adapted to engage the edge of said recess to limit its upward movement under the influence of the spring, and a lock mounted on the said tab independently of said shoulder having a bolt which when shot projects beneath said stop to prevent downward movement thereof. 55

In testimony whereof I have signed my name to this specification.

HARRY ALPHONSE WIDMER.
